UNITED STATES PATENT OFFICE.

EDWARD A. FARR, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A TOASTER-FRAME.

46,897.

Specification for Design.

Patented Feb. 2, 1915.

Application filed October 24, 1914. Serial No. 868,534. Term of patent 7 years.

To all whom it may concern:

Be it known that I, EDWARD A. FARR, a citizen of the United States, residing at Meriden, New Haven county, Connecticut, have invented a new, original, and ornamental Design for a Toaster-Frame, of which the following is a specification, reference being had to the accompanying drawing, forming a part thereof, in which

the figure is a perspective view of a toaster-frame embodying my new design.

I claim:

The ornamental design for a toaster frame as shown.

EDWARD A. FARR.
